UNITED STATES PATENT OFFICE.

HENRY S. BREWINGTON, OF BALTIMORE, MARYLAND.

BOTTLE-CAP.

No. 895,066.

Specification of Letters Patent.

Patented Aug. 4, 1908.

Application filed August 5, 1907. Serial No. 387,049.

To all whom it may concern:

Be it known that I, HENRY S. BREWINGTON, a citizen of the United States, residing at Baltimore city, State of Maryland, have invented certain new and useful Improvements in Bottle-Caps, of which the following is a specification.

My invention relates to an improvement in bottle caps or closures, the primary object 10 being to provide a cap which will ordinarily seal or make an air tight closure without the use of a separate packing, except in certain exceptional cases of goods being bottled under extraordinary high pressure or highly 15 charged, it may in instances of this kind be found advantageous to use a packing such as I have provided and the use of which will be hereinafter explained. The further object of 20 my invention being to eliminate the use of a packing separate from the cap as well as the feature of the packing coming in contact with the contents of the package upon occasions when the use of an additional packing is made necessary.

25 It is a well known fact that in the use of cork and similar material as a packing where the packing comes into contact with the contents of the package, it is necessary to process the cork or treat the packing by some method 30 to prevent the contents from deteriorating by reason of the escape of the gas through the pores of the cork or from becoming contaminated by the materials of which the packing is made. That this may be accomplished, I have provided a cap having a depending flange which is adapted to be pressed, curled, spun or crimped under the bead on a bottle head and by this means is secured in locking contact therewith.

40 In the manufacture of my cap I provide a cap made of a single piece of sheet metal, preferably of aluminum, and the packing is formed entirely from the body portion of the cap, outside of the saving as to the cost of 45 producing a cap made in this manner as compared with others where a separate packing and lining are used, I provide a cushion formed by a plurality of layers of the metal by reason of the metal being bent over on 50 itself and this cushion packing so formed will conform to the various shapes and degrees of imperfections of the bottle heads in such a manner as to insure a proper closure.

I have exhibited two forms of caps, each made from a single piece of sheet metal, both 55 being practically the same, producing the same result save that a packing ring may be used in connection with the modified form to an advantage where the imperfections and variations of the different bottle heads are 60 such as to occasion its use, that these variations and imperfections may be overcome and thereby prevent the bottles from becoming useless and the financial loss occasioned thereby. It will be found, however, 65 that there will be very little requirement as to the use of the packing, save on the occasions hereinabove enumerated, as the metal packing formed from the cap when the cap is placed on a bottle head and pressure 70 applied will become compressed, and in compressing the packing it will cover the bead on the bottle head and extend beyond the inward portion thereof and embrace the inner wall of the bottle neck; and by a similar de- 75 gree of extension it will be pressed closely against the exterior wall of the bead on the bottle head, thereby providing the several points of sealing contact between the packing and the bead on the bottle head. 80

With the foregoing objects in view, my invention consists in certain novel features of construction and combination of parts, which will be hereinafter described and pointed out in the claims. 85

In the accompanying drawings Figure 1, is a perspective view of the cap; Fig. 2, is a cross-section view of the cap shown in Fig. 1, showing the packing ring secured therein; Fig. 3, is a vertical cross-section view, showing the cap and bottle head; Fig. 4, is a perspective view of a modified form of cap; Fig. 5, is a perspective view of a modified form of cap; Fig. 6, is a cross-section view of the cap shown in Fig. 5; Fig. 7, is a vertical cross section view of the modified form of cap secured on a bottle head; Fig. 8, is a perspective view of the packing ring, and Fig. 9, is a cross section view of the modified form of cap, showing the packing ring se- 100 cured therein.

A, is a metallic cap made from a single piece of sheet metal; 1, is a depending flange; 2, is a circumferential groove in the flange located near the top portion thereof; 105 3 is a circumferential bead formed on the

outer top edge of the cap above the groove 2. The metal packing 4 formed by the walls of the groove 2 which walls are extended inwardly so when the cap is placed upon 5 the bottle head B, they will extend transversely across the bead 5 of the bottle head, and when downward pressure is applied to the cap the walls will collapse and be pressed together so as to conform to the bead 5 10 of the bottle head, the double thickness of metal forming the walls constituting a cushion packing, forming a sealing contact with the bead 5 of the bottle head B, the depending flange 1 being pressed or spun 15 under the bead 5, as shown in Fig. 3, while the downward pressure is applied to the cap, so that when the downward pressure on the cap is released the sealing contact between the packing 4 and the bead 5 on the bottle 20 head is retained. The same may be said as to the use of the form of cap as shown in Fig. 4, save that the depending flange 6, which is crimped in this style of cap is squeezed or crimped under the bead 5, on 25 the bottle head B. In all other respects the construction and the method of securing it on the bottle head are the same as have just been described in reference to the cap having a plain depending flange.

30 In the modified form of cap, as shown in Figs. 5, 6, 7 and 9; C, represents the cap, made from a single piece of sheet metal, and in construction is but a reversal of groove forming the packing. In Fig. 1, the groove 35 is formed exteriorly within the depending flange, while in the modified form shown in the figure above referred to, the packing is formed wholly within the body portion in the manner now about to be described.

40 The cap C is provided with a depression 7, the walls of the said depression at the extreme bottom portion thereof are then expanded forming a circumferential groove 8, with the wall 9 of the groove 8 flush 45 against the inner wall of the depending flange 10. Before this process of expanding the depression 7, the packing ring 11 is secured within the cap and around the depression, so that when the expansion takes 50 place the packing ring will occupy the space 12, as shown in Figs. 6 and 9. The method and manner of securing the cap on the bottle head are the same as has already been described, the only difference in the 55 two respective caps being that in the cap first described the packing is formed exteriorly within the flange and in the second instance it is formed interiorly wholly within the body portion.

60 I have shown a packing ring (which ring may be made of any suitable material) in conjunction with the modified form just described; it is conceded that a packing ring may also be used in conjunction with the cap

first described as may be desired, under the 65 conditions hereinbefore set forth.

Slight changes might be resorted to in the form and arrangement of the several parts herein described, without departing from the spirit and scope of my invention, hence I do 70 not desire to limit myself to the exact construction as herein set forth; but,

Having fully described my invention, what I claim as new and desire to secure by Letters Patent, is:

75

1. A bottle cap made from a single piece of sheet metal, comprising a depending flange and a packing formed from the depending flange, substantially as described.

2. A bottle cap made from a single piece of 80 sheet metal, comprising a depending flange, provided with a circumferential groove therein forming a packing within the cap, substantially as described.

3. A bottle cap made from a single piece of 85 sheet metal, comprising a depending flange provided with a circumferential groove therein, the portion of the said depending flange above the said groove forming a circumferential bead on the outer edge of the 90 said cap and adjacent to the said groove, the walls of the said groove when compressed forming a packing within the cap, substantially as described.

4. A bottle cap and a packing formed there- 95 in, made from a single piece of sheet metal, substantially as described.

5. A bottle cap made from a single piece of sheet metal provided with a depending flange, a packing formed wholly within the cap and 100 being a part thereof, the said packing adapted to be compressed when secured on the bead of a bottle mouth, substantially as described.

6. A bottle cap comprising a depending 105 flange and a packing made from a single piece of sheet metal, substantially as de- scribed.

7. A bottle cap made from a single piece of sheet metal, comprising a depending flange 110 provided with a circumferential groove therein, a packing ring secured within the said groove, the said groove adapted to be compressed thereby forming a packing within the cap, the said packing ring affording an 115 additional cushion to the packing so formed for the purpose of overcoming the variations and imperfections of a bottle head, substantially as described.

8. A bottle cap made from a single piece of 120 sheet metal provided with a depending flange, a packing formed wholly within the cap and being a part thereof, a packing ring secured within the said packing, the said packing adapted to be compressed with the packing 125 ring therein contained when secured on the bead of a bottle mouth, substantially as de- scribed.

9. A bottle cap comprising a depending flange provided with a circumferential groove therein, the said groove adapted to be compressed thereby forming a packing within the cap, whereby a complete cap and packing is formed from a single piece of the same material, substantially as described.

In testimony whereof I affix my signature in presence of two witnesses.

HENRY S. BREWINGTON.
